PISTON

Ray E. Day, Detroit, Mich.

Application July 18, 1932, Serial No. 623,064
Renewed April 18, 1936

3 Claims. (Cl. 309—11)

This invention relates to pistons for internal combustion engines, and particularly to pistons made from aluminum alloy, which on account of the relatively high co-efficient of expansion of the metal, expand to such a degree under operating conditions as to require either an undesirable initial clearance within the cylinders, or the provision of means to control the expansion so that a substantially uniform clearance may be maintained during operation.

I have found that there are two principal factors which control the successful manufacture and sale of a low price commercially practical piston. First, the design of the piston must be simplified in order to facilitate casting of the pistons and to reduce the cost of manufacture. Second, the piston must be so constructed in simplified manner as to take care of expansion and contraction under operating conditions, maintain a nearly uniform operating fit in the cylinder, and effectively guide the piston in order to prevent rocking or tilting of the piston and piston slap.

An object of the present invention is to provide a piston of simplified construction which can be produced cheaply and which at the same time is constructed in improved manner so as to have the desired high degree of efficiency in operation without resorting to structural expedients, many of questionable value, as heretofore.

Other objects of this invention will appear in the following description and appended claims, reference being had to the accompanying drawing forming a part of this specification wherein like reference characters designate corresponding parts in the several views.

Fig. 1 is a side elevation of a piston embodying my invention.

Fig. 2 is a vertical section taken substantially along the line 2—2 of Fig. 1, looking in the direction of the arrows.

Fig. 3 is an elevation of the opposite side of the piston shown in Fig. 1.

Fig. 4 is a horizontal section taken substantially along the line 4—4 of Fig. 2 looking in the direction of the arrows.

Fig. 5 is a view similar to Fig. 3 showing a modified form of construction.

Before explaining in detail the present invention it is to be understood that the invention is not limited in its application to the details of construction and arrangement of parts illustrated in the accompanying drawing, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

Referring now particularly to the drawing, I

have shown an aluminum alloy piston having a head 9 provided with piston ring grooves 10 separated by lands 10a, a skirt 11, piston pin bosses 12 and 13 provided with piston pin openings 14 and 15, respectively. The piston head 9 is provided with a transverse reinforcing web 16 which has depending portions 16a formed integrally with the piston pin bosses 12 and 13. The skirt portion of the piston is provided with an internal circumferential reinforcing rib 17 preferably located immediately below the horizontal slit 18 which serves to separate a portion of the head 9 from the skirt 11.

The skirt 11 is provided at one side with a relieved area shown as a whole at 19, which surrounds the piston pin opening 14 and extends to the top of the skirt on one side of and above the opening, as shown at 19a. On the opposite side of the piston pin opening 14, the relieved area 19 terminates at a point adjacent the top of the skirt to provide a bearing strip or portion 21 which preferably tapers off slightly, as shown at 21a, toward the open relieved area. Within the relieved area the skirt is provided with a curved slot having a substantially arcuate portion 23 and a horizontally extending portion 23a. The portion 23 of the slot terminates at a point adjacent and slightly below the taper 21a. The horizontal portion 23a of the slot extends along the lower edge of the relieved area 19 adjacent the curved bearing portion at the bottom of the skirt. The relieved area 19 is unbalanced or divided into two unequal portions. The portion *a* on one side of the piston pin opening, namely the compression or low thrust side of the piston, is wider than the portion *b* on the opposite side of the piston pin opening, namely the explosion or high thrust side.

Referring to Fig. 3, the opposite side of the piston skirt is provided with a similar relieved area 20 surrounding the piston pin opening 15 and extending to the top of the skirt at one side of the opening, as shown at 20a. On the other side of the opening, this relieved area terminates at a point below the top of the skirt or the horizontal slot 18 to provide a bearing strip or portion 22 tapered off at 22a. The skirt within the relieved area 20 is likewise provided with a curved slot having an arcuate shaped portion 24 and a horizontal portion 24a. It will be seen that the relieved areas 19 and 20 and their associated parts are identical on both sides of the piston.

The side of the skirt 11, at a point between the piston pin bosses, is traversed by a substantially vertical slit 25, which, in actual practice, preferably extends from the bottom edge of the skirt to the horizontal slit 18. The lower portion of the skirt is provided with an internal circumferential reinforcing rib 26, similar to the rib 17, 60

which is located immediately below the horizontal portions 23a and 24a of the curved slots. The lower edge of the piston skirt may be provided with an inturned circumferential flange 21 which serves as additional reenforcing means for the skirt.

Referring now to Fig. 5, I have shown a modified form of my invention in which the piston therein comprises a head 9 having piston ring grooves 10, a skirt 11 and a horizontal slit 18a which extends part way around the piston between the head and skirt. The skirt 11 is provided at each side with a relieved area 28 surrounding the piston pin opening 15 and extending to the upper edge of the skirt at a point immediately above the opening 15. The area 28 however, adjacent its side edges is terminated at points adjacent the upper edge of the skirt to provide a pair of opposed horizontal bearing strips or portions 28a and 28b. The relieved area 28 is provided preferably with a substantially U-shaped curved slot 29 which conforms to the shape of the piston pin opening 15 and extends around the bottom and sides thereof, the lower portion of the curved slot extending preferably to the extreme lower edge of the relieved area 28 adjacent the lower bearing surface of the skirt. The other structural features of the piston of Fig. 5 are identical with those of the preceding figures. It will be noted that the relieved area 28 is unbalanced and is wider on the split side of the piston as shown at c, than on the opposite or high thrust side of the piston, as shown at d.

From the foregoing it will be noted that the head and skirt are separated from each other on one side of the piston pin bosses by the horizontal slit 18. On this same side the skirt is longitudinally split by the substantially vertical slot 25, so that one side of the piston is freely compressible. The piston pin bosses are partially separated from the skirt by the slots 23, 23a; 24, 24a; and 29, which permit the bosses to expand or move outwardly with the head without transmitting this expansion to the annular bearing portion below the bosses or to the split side of the skirt. The separation of the major part of the bosses from the skirt gives an appreciable amount of freedom between the bosses and the skirt and permits the entire lower portion of the skirt to remain substantially round at all times. The ribs or annular trusses 17 and 26 assist materially in maintaining the skirt portion round while permitting expansion and contraction thereof. If the skirt were not separated from the bosses by these curved slots, it would be drawn out of round and excessive wall pressure would be set up in the direction of the wrist pin bosses. In practice, the piston is placed in the engine cylinder in such a position that the reaction due to the compression will be directed against the relatively resilient or split side of the piston, while the reaction due to the explosion, which is much greater, will be directed against the side where the head and skirt are integral or continuous.

It will be seen that the widest portion of each unbalanced relieved area is on the compression or split side of the piston, whereas the smaller portion of the relieved area is on the explosion or high thrust side. Since the high thrust side of the piston is subjected to greater pressure than the low thrust side I have found it preferable to have a larger bearing surface on the high

thrust side. By thus reducing the area of the bearing surface on the low thrust or compression side of the piston it will be seen that the flexibility of that side of the piston is increased to eliminate any possibility of binding of the piston.

With previous types of pistons having resilient skirt portions provided with open relieved areas, it has been found that there was a tendency of the piston to rock or tilt in the cylinder, causing the objectionable slapping of the piston. This is obviated in the construction shown in Figs. 1 to 4 by the bearing strips or portions 21 and 22, located above the relief on the resilient side of the piston. These bearing strips or surfaces also help to guide the piston during its reciprocation within the cylinder. In the form shown in Fig. 5, two horizontally disposed bearing strips or portions 28a and 28b are provided, which, together with the bearing portion of the skirt below the relief 28, serve to guide the piston in the cylinder and also to prevent it from rocking. These bearing portions thus assist in guiding the piston at points between the skirt and the lower ring groove, but they are interrupted or relieved in the integral relieved areas through which the bosses are united to the head so as not to interfere with the outward movement of the bosses.

I claim:

1. In a piston, the combination of a head, a skirt, and piston pin bosses, the head and skirt being continuous at one side of the bosses and separated at the other side by a circumferential slit, the skirt at said last named side being split between the bosses, said piston having a relieved area around each piston pin opening and a curved slot located wholly within the relieved area spaced from and extending partly around each opening to partially separate the piston pin boss from the skirt, and a narrow bearing portion extending into the relieved area between the curved slot and said circumferential slit.

2. In a piston, the combination of a head, a skirt, and piston pin bosses, the head and skirt being continuous at one side of the piston and separated at the other side of the piston by a circumferential slit, the piston having a relieved area around each piston pin opening and a curved slot located wholly within the relieved area spaced from and extending partly around each opening to partially separate the piston pin boss from the skirt, said slot terminating below said slit within said area, and an annular rib extending horizontally inside the skirt in a plane immediately below said curved slot.

3. In a piston, the combination of a head having grooves therein, a skirt and piston pin bosses, the head and skirt being continuous at one side of the bosses and separated at the other side thereof by a circumferential slit, the piston having a relieved area around each piston pin opening and a substantially U-shaped slot located wholly within the relieved area below the ring grooves spaced from and surrounding a portion of the opening to separate the piston pin boss from the skirt substantially entirely at opposite sides of and below the piston pin opening, and unbalanced bearing strips extending into said relieved area from opposite side edges thereof and having their inner ends spaced apart, said ends being located above and adjacent the ends of said U-shaped slot.
